UNITED STATES PATENT OFFICE.

GEORGE ALLEN LANE, OF LAKESIDE, CALIFORNIA, ASSIGNOR OF ONE-HALF TO JOSEPH F. MARTIN, OF LAKESIDE, CALIFORNIA.

COMBINATION BIT AND REAMER.

SPECIFICATION forming part of Letters Patent No. 700,430, dated May 20, 1902.

Application filed September 30, 1901. Serial No. 77,100. (No model.)

To all whom it may concern:

Be it known that I, GEORGE ALLEN LANE, a citizen of the United States, residing at Lakeside, county of San Diego, State of California, have invented an Improvement in Combination Bits and Reamers; and I hereby declare the following to be a full, clear, and exact description of the same.

My invention relates to improvements in well-boring tools. Its object is to provide a drill for use in oil and other wells which will ream out the well below the casing at the same time the bore of the well is advanced and which drill can also be withdrawn through the casing.

The invention consists of the parts and the constructions and combinations of parts hereinafter described and claimed.

Figure 1 is a vertical section through a well, showing the boring-tool. Fig. 2 is a view of the lower portion of the bit. Fig. 3 is a bottom view of the bit.

A represents a well-casing of any desired diameter, in which the drill-rod 2, carrying the drill B, operates. The drill consists of a flat bar of steel, having a reduced shank portion 3, adapted to be secured in the box 4 on the end of the drill-rod. The drill is made with one edge 5 approximately parallel with the shank-axis, while the other or "front" edge 6, as it may be called, is longer and diverges from said axis, so that the point or toe 7 of the drill would in its revolution about said axis describe an arc of greater radius than one-half the drill width. The lower or cutting end of the drill is inclined downwardly from the bottom of the edge 5 to the toe-point, so that the outline of the drill is suggestive of a scalene triangle. This end is dressed to have a plane surface portion or heel 8 and a beveled or cutting edge or toe portion 9. Tapered grooves, as 10, are cut on either side of the drill. These grooves are deepest and widest along the edge of the cutting-face and gradually grow shallower and narrower toward the upper end of the drill. A cross-section of the bit near its lower end would be essentially in the form of a figure 8. The

bevel of the face 9 extends between and rearward of the center of the grooves, so that between the grooves the face 9 presents a narrow cutting edge. The grooves act as passage-ways for the mud and fluid displaced by the falling drill. The boring and reaming are done entirely by the face 9 and the toe-point 55 7, while the flat heel portion 8 acts on the thick fluid and mud as the bit is dropped to force the long cutting-point against the wall, and thus to cut the hole as the rod is revolved large enough to admit the casing-shoe. This 60 "underreaming," as it is termed, is primarily effected by reason of having the point of attachment of the bit or drill with the rod off the center of the body of the drill and on the side of the center opposite from the toe-point. 65

The bit may be removed from the well at any time by simply withdrawing the rod upon which it is secured. The toe portion of the bit strikes the lower edge of the casing and causes the bit, whose width is less than the 70 interior diameter of the casing, to slide up into the casing.

Having thus described my invention, what I claim, and desire to secure by Letters Patent, is—

A drill consisting of a body portion having its lower end inclined in relation to the axis of said body, the rear portion of said end surface being plane to form an inclined flat heel, and the forward or toe portion of this same 80 inclined lower surface of the drill having oppositely-beveled surfaces forming a cutting edge, and tapered grooves upon the sides of said drill, said grooves being widest and deepest at the lower end of the drill, and said beveled lower surface extending from the edge of the long side of the drill to a point between and rearward of the center of the grooves, substantially as herein described.

In witness whereof I have hereunto set my 90 hand.

GEORGE ALLEN LANE.
